CLAIM

The ornamental design for a slide lamp, substantially as shown and described.

DESCRIPTION

FIG. 1 is a top perspective view of a slide lamp showing our new design.

FIG. 2 is a bottom perspective view of the slide lamp.

FIG. 3 is a front view of the slide lamp.

FIG. 4 is a rear view of the slide lamp.

FIG. 5 is a left side view of the slide lamp, wherein the left and right side views are mirror images.

FIG. 6 is a top view of the slide lamp; and,

FIG. 7 is a bottom view of the slide lamp.

The broken lines showing environment structure are for illustrative purposes and form no part of the claimed design.
